UNITED STATES PATENT OFFICE.

ARTHUR G. L. NEIGHBOUR, OF BRIGHTON, VICTORIA, AUSTRALIA.

MAGNETO-ELECTRIC IGNITION MACHINE.

Application filed April 2, 1923. Serial No. 629,324.

To all whom it may concern:

Be it known that ARTHUR GEORGE LLOYD NEIGHBOUR, a subject of the King of Great Britain, residing at 1 Oak Grove, Brighton, in the State of Victoria, Commonwealth of Australia, has invented certain new and useful Improvements in or Relating to Magneto-Electric Ignition Machines, of which the following is a specification.

10 This invention relates to improvements in or relating to magneto electric machines, ordinarily termed magnetos, which generate currents that periodically reverse in direction and increase in strength from zero to 15 maximum values and refers more especially to interrupters or contact breakers of said machines.

The object of the present invention is to 20 provide an interrupter or contact breaker of simple construction which can be readily adapted to function efficiently in either direction of rotation of a magneto as commonly employed for ignition purposes in internal combustion engines.

25 Reference being had to the drawings illustrating the invention:

Figure 1 is a view in end elevation of an 30 interrupter constructed in accordance with the invention.

Figure 2 is a view in sectional elevation taken on the dotted line II—II of Figure 1.

In these drawings the numeral 52 designates a contact breaker base plate which is secured to a contact breaker shaft 51 in the usual manner by a central screw 66 which bears upon and passes through an insulated metal block 67 mounted on the said base plate 52. This screw 66 is axially disposed within and insulated from the contact breaker shaft 51, and at its inner end said screw engages with a fixed insulated member connected with the primary winding of the armature of the machine.

The insulated metal block 67 is accordingly electrically connected with the outer end of the primary winding at all times. Said insulated block 67 is constructed with two radial branches 72 which are disposed on opposite sides of a diametral plane with which said branches make equal angles.

Screws 73 are passed through and insulated from the base plate 52, and these screws engage with tapped holes in the branches 72 of the insulated block 67. By means of the screws 73 said insulated block

is fixed securely to the base plate 52 even when the central screw 66 is removed.

In said diametral plane and on the side of the axis of rotation remote from the branches 72 and at a required distance from 60 said axis, is positioned a pivot 74, which is securely fixed in the base plate 52.

On the pivot 74 is mounted a bush 75 of insulating material which forms a bearing for the contact breaker lever 76. This lever 65 is of the usual bell crank construction having a fibre wiper 77 at one end and a contact 78, hereinafter referred to as the movable contact at the opposite end.

A co-operating contact 79 termed the insulated contact is mounted on the screw 80 which is adapted to fit threaded holes 81 in the branches 72. The screw 80 is capable of endwise adjustment and is provided with a lock nut 82 in the usual manner.

In said diametral plane, and formed integrally with the base plate 52 and positioned between the branches 72, is an outwardly projecting lug 83 to which is attached one end of a spring 84 by a screw 85. The spring 84 at its opposite end is attached to said lever 76 by a screw 86. Said spring 84 functions in the usual manner to maintain the movable contact 78 upon the insulated contact 79.

A hole is made through the boss of the lever 76, and this hole is made of such diameter that it fits neatly the exterior of the bush 75. An insulating washer 88 is interposed between the lever 76 and the base 90 plate 52.

A flat spring 89 bears upon the outer end of the bush 75 and retains the latter and the lever 76 in place upon the pivot 74. The central screw 66 passes through a hole 95 made in the opposite end of the spring 89 and the latter is clamped between the head of said screw and the insulated block 67, but not so tightly as to prevent its being turned aside when it is necessary to remove the lever 76.

The movable contact 78 is separated from the insulated contact 79 in the usual manner, by impact of the fibre wiper 77 with cams 90 fixed concentrically around the contact breaker.

The contact breaker above described can be quickly adjusted to operate in either direction of rotation with equal efficiency.

It is imperative for efficient operation of 110

a contact breaker that the fibre wiper 77 should trail behind or follow the pivot 74 of the contact breaker lever 76 during rotation. If the fibre wiper 77 leads or moves 5 in advance of the pivot 74, the former will wear and chattering of the lever will occur and undue wear of the bush 75 will result.

In Figure 1 the contact breaker is shown 10 adjusted for operation in a clockwise or right-handed direction when viewed as customary from the opposite end or driving end of the magneto.

The lever 76 having no lateral projections 15 and being symmetrically supported on the bush 75 may be removed from the pivot pin 74 and turned over so as to bring its respective arms into precisely similar positions on opposite sides of the diametral plane 20 passing through the pivot pin 74 and the spring supporting lug 83. The spring 84 is adjusted to extend from the opposite side of the lug 83 and the screw 80 bearing the insulated contact 79 is transferred to the hole 25 81 in the other branch 72 of the insulated block 67.

It will be observed that the various parts 30 after reversal and transference, take up exactly similar positions on the opposite sides of the diametral plane mentioned above. After adjustment of the insulated contact 35 79 has been effected to give the required break or distance between the contacts 78 and 79 when separated, it will be found that the contact breaker will operate in the opposite direction of rotation with equal efficiency.

It will be obvious to persons skilled in the art that a contact breaker constructed in the

manner above described has a considerable 40 advantages over the usual type of contact breaker, for in addition to the ease with which it may be altered to operate in either direction, it simplifies manufacture in that only one contact breaker is required instead of two suited respectively to clockwise and 45 anticlockwise directions of rotation.

I claim:—

In a magneto, a reversible contact breaker having a base plate, a substantially V-shaped insulated block concentrically mounted on 50 the base plate, a pivot on the base plate on the opposite side of the axis thereof to that on which the radial branches are situated and positioned in a diametral plane which passes between the radial branches of 55 the V-shaped block, an insulating washer positioned around the pivot and bearing on the base plate, a cup-shaped insulating bushing covering the exposed portion of the pivot, said bushing being shouldered on its 60 exterior, a reversible contact carrying lever mounted on the reduced portion of said bushing and adapted to oscillate freely thereabout, means for securing a contact to either of the radial branches of the V-shaped 65 block, a fixing screw for securing the V-shaped block in place, and a spring rigidly secured at one end by the fixing screw and having its other end bearing on the cup-shaped bushing to maintain said bushing 70 and contact carrying lever in position.

In testimony whereof I affix my signature.

ARTHUR G. L. NEIGHBOUR.
